Primary Examiner — Dana K Weiland

(57) **CLAIM**

The ornamental design for a pen display, as shown and described.

DESCRIPTION

FIG. 1 is a perspective view of a pen display showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of the portion of the pen display shown within the area designated as 8 in FIG. 1;

FIG. 9 is an enlarged view of the portion of the pen display shown within the area designated as 9 in FIG. 1;

FIG. 10 is an enlarged view of the portion of the pen display shown within the area designated as 10 in FIG. 2; and,

FIG. 11 is an enlarged view of the portion of the pen display shown within the area designated as 11 in FIG. 2.

The broken lines in the drawings illustrate portions of the pen display that forms no part of the claimed design.

1 Claim, 7 Drawing Sheets
